UNITED STATES PATENT OFFICE

JAMES A. POWELL, OF READING, PENNSYLVANIA

JET-TYPE WATER HEATER

Original application filed June 27, 1922, Serial No. 571,267. Divided and this application filed February 26, 1927. Serial No. 171,161.

This invention relates to water heaters, and particularly to heaters of the jet type, and this application is a division of my application filed June 27, 1922, and serially numbered 571,267, which matured into Patent 1,621,853 on March 22, 1927.

An object of the invention is to produce a jet type water heater which will operate effectively and efficiently under widely varying conditions of steam and water flow.

Fig. 1 of the drawing accompanying and forming a part hereof, is a transverse section of a water heater constituting one embodiment of my invention, and Fig. 2 is 15 a view in section taken on line 11—11 of Fig. 1, of a divided water box.

It is well established that the over-all efficiency of a power plant is increased by heating the feed water before delivering it 20 to the boilers. To accomplish this economically, it is necessary to avoid a waste of heat in the operation of withdrawing air or other non-condensable fluids from the heater. It is also essential to avoid the 25 loss of steam particularly on ship-board or in localities where water suitable for feed water purposes is scarce.

An object of my invention, therefore, is the production of a jet type water heater 30 which operates economically under widely varying conditions of steam and water flow and which avoids waste of heat or steam in the operation of withdrawing the non-condensable fluids from the heater.

It is usual power house practice to heat 35 the feed water with steam exhausted from one or more steam driven auxiliaries.

The feed water is made up in part of condensate received from the condensers 40 serving the prime movers and where jet condensers are employed it is made up in part of raw water, consequently, the quantity of water delivered to the feed water heater varies with variations in the load on 45 the prime movers, while the flow of steam from the auxiliaries is more constant. It is, therefore, considered best practice to so proportion the number of auxiliaries exhausting into each heater that the heaters 50 will operate economically under conditions

occasioned by the most normal load on the prime movers. With heaters now in use, a variation above and below such conditions will occasion a loss in the efficiency of the heater. Under super-normal load conditions 55 the increased volume of water is not heated to the most economical temperature and under subnormal load conditions, a loss is occasioned by the delivery of excess steam to the heater.

With feed water heaters such as are now in use the permissible range of temperature fluctuations is extremely limited, and in addition, heaters are so constructed that they not only waste steam under conditions of 60 low water flow, but actually accentuate the waste by occasioning an increase in the delivery of heating steam to the heater under such conditions. This increase in the amount of heating steam delivered is occasioned by 65 the fact that a decrease in the amount of water decreases the capacity of the heater to absorb heat and to condense the steam delivered to it. The surplus steam in the heater, therefore, increases the back pressure 70 on the auxiliaries and this in turn reduces the efficiency of the auxiliaries and causes them to demand more steam in order to accomplish the work required of them. Under such conditions the surplus steam 75 must be discharged from the heater and it is ordinarily vented to the atmosphere with a resultant waste of both heat and water.

While the jet type of heater is superior 80 to other types both from the standpoint of operation, first cost and maintenance, the difficulties encountered in other heaters are accentuated in the jet type and particularly under conditions of low water supply. This 85 is due to the fact that a jet type of heater, such as now employed when designed for normal load conditions on the main generating units is incapable of occasioning the necessary intimate intermingling of the water and steam under subnormal load conditions. As a result, much of the steam delivered to the heater is not subjected to the cooling effect of such water as is present in 90 the heater and is, therefore, vented to the 95 heater and is, therefore, vented to the 100

atmosphere at substantially its incoming temperature.

In carrying out my invention, I provide a heater in which a number of groups of spray nozzles are employed and I also so locate and arrange the different groups of nozzles that an effective carrier of water spray is interposed between the steam inlet of the heater and the air outlet, even under extreme conditions of low water flow. With this arrangement, the heater operates economically under low water flow conditions and is also capable of operating with high efficiency under conditions of maximum water flow since as the water flow increases, one or more groups of spray nozzles are rendered effective in delivering water spray to the heater.

In the drawings I have shown a form of heater embodying the desirable features of the heater illustrated in my above mentioned application, which matured into Patent No. 1,621,853. As shown, the heater is equipped with a single steam header but is provided with a divided water box so arranged that the water entering the heater will be broken up into a mass of separate drops of spray by spray nozzles even under conditions of low water flow. As shown, the casing 30 is provided with an air offtake port 35, a water discharge port 36 and two series of spray nozzles 31 and 32. Heating steam from auxiliaries or any other source of supply is preferably delivered to the upper portion of the heater through a port 39.

The spray nozzles 31 communicate with a water box 34 which receives its supply of water through a pipe 16'. This water box preferably extends half way around the casing 30 and the nozzles are preferably of less capacity than the nozzles 32 so that they will break the water up into spray even under conditions of low water flow. The nozzles 32 communicate with a water box 36 which is, in effect, a continuation of the water box 34 except that its water distributing space is partitioned off from that of the box 34. Water box 36 is in effect a continuation of water box 24 because box 36 receives water supply through a pipe or passage 17', which communicates with or is tapped off the pipe 16', as shown by the broken pipe connections in the drawings. Under such conditions, the nozzles 32 only receive water after the supply is in excess of that which can be delivered through the nozzles 31 and as a result the nozzles 31 receive a substantially constant flow of water, even under varying water flow or low head conditions, whereas the nozzles 32 receive water only under conditions of full flow or high head.

I have also shown a combining cone 19' which corresponds in function, location and arrangement, to the combining cone 19 of said application. In addition, I have illus-

trated an upwardly projecting annular flange 37, notched at its upper edges and so arranged as to segregate a water receiving channel 38 which is located immediately below the spray nozzles 31 and 32 and surrounds the interior of the casing 30. Under such conditions, such water as is delivered to the interior of the heater by either the spray nozzles 31 or 32 without being broken up into spray, collects in the channel 38 and overflows over the notched edge of the flange 37. This water is therefore broken up into separate streams by the notches and is further broken up into drops as it falls through the interior of the heater. The channel 38 may be subdivided by partitions so that each subdivision receives water from one series of nozzles.

The channel 38 which is formed in part by the notched flange 37 may be considered as a V-notch meter or V-notch weir.

It will be apparent that all the steam entering the port 39 must pass through a barrier of water spray or finely divided water before arriving at the air offtake port 35. It will also be apparent that the heater is highly effective in breaking up the water flow into a mass of spray even under widely varying conditions of water flow.

It is preferable to employ an air pump or air ejector for withdrawing the non-condensable vapors, air or other non-condensable fluids through the port 35. The water discharge ports 36 may communicate with a storage tank or it may communicate with a tail pipe or with the intake port of a pump for delivering the heater water to a storage tank or other suitable receptacle.

While I have described an embodiment of my invention, it will be apparent to those skilled in the art that various changes, modifications, substitutions, additions and omissions may be made in the apparatus illustrated, without departing from the spirit and scope of the invention, as set forth by the appended claims.

I claim:

1. In combination in a jet type water heater, a shell, a divided water box, a separate water delivery port communicating with each division of the water box, a separate series of spray nozzles communicating with each division of the water box, each series of nozzles being of different capacity from the other series, a steam inlet port located above the water box, an air offtake port located below the water box and a water collecting channel located between the spray nozzles and the air offtake port.

2. In combination in a jet type water heater, a shell having a steam inlet port and an air offtake port formed therein, a divided water box located between said ports and having a separate water inlet port communicating with each division thereof, spray

nozzles communicating with each division of said water box and receiving water therefrom, each series of nozzles being of different capacity from the other series, a converging cone extending downwardly below said water box and a water receiving channel located between said cone and said spray nozzles.

3. In combination in a jet type water heater, a shell having a steam inlet port, an air off-take port, and a water discharge port, an annular water box located between said inlet port and said air off-take port, a partition dividing said box into compartments, a separate series of spray nozzles communicating with each compartment of said box, one series of said nozzles being of greater water delivering capacity than the other, a converging water collecting passage extending downwardly within said shell from a point adjacent said water box to a point below said air off-take port and an independent water supply communicating with each compartment of said water box.

4. In combination in a jet type water heater, a shell provided with a steam inlet port, a water discharge port and an air off-take port located between said first mentioned ports, a divided water box extending around said shell and located between said inlet port and said air offtake port and having a separate series of spray nozzles communicating with each division of said box, an annular water collecting channel located below said nozzles and above said offtake port and a downwardly converging combining cone below said channel and between it and said offtake port.

5. In combination in a jet type water heater, a shell provided with a steam inlet port, a water discharge port and an air off-take port located between said first mentioned ports, a divided water box located between said inlet port and said air offtake port, each division thereof provided with a series of water discharge nozzles of different capacity from the water discharge nozzles of other divisions, an annular water collecting channel between said nozzles and said air offtake port and a downwardly converging combining cone between said channel and said air offtake port.

6. In combination in a jet type water heater, a shell having a steam inlet port at the top thereof, a water discharge port at the bottom thereof and an air offtake port intermediate said first mentioned ports, a divided water box between said inlet port and said air offtake port having a series of discharge nozzles communicating with each division thereof and of different capacity from the supply nozzles of other divisions, the nozzles of each division being located in substantially the same plane and arranged to discharge fluid in streams intersecting

each other, and a separate water supply communicating with each division of said water box.

7. In combination in a jet type water heater, a shell provided with a steam inlet port, a water discharge port and an air off-take port located between said first mentioned ports, a divided water box surrounding said heater and located between said inlet port and said air offtake port, each division of which is provided with a series of water discharge nozzles of different capacity from the nozzles of the other division, an annular water collecting channel located immediately below said nozzles and provided with a notched overflow flange, and a downwardly converging combining cone located within said heater and immediately below said channel.

8. In combination in a feed water heating system, a jet type heater comprising a shell having a steam inlet port and a water inlet port and provided with a series of spray nozzles located in substantially the same plane and arranged to deliver water to be heated in intersecting streams to the interior thereof, an annular V-notch weir located within said heater and immediately below said nozzles, and means for maintaining a vacuum in said heater.

In testimony whereof, I have hereunto set my hand this 24th day of February, 1927.

JAMES A. POWELL.
